UNITED STATES PATENT OFFICE.

GEORGE F. A. OCHS, OF NEWARK, NEW JERSEY.

RAILROAD-TIE.

1,344,926.

Specification of Letters Patent. Patented June 29, 1920.

Application filed November 25, 1919. Serial No. 340,623.

To all whom it may concern:

Be it known that I, GEORGE F. A. OCHS, a citizen of the United States of America, residing at Newark, in the county of Essex and 5 State of New Jersey, have invented new and useful Improvements in Railroad-Ties, of which the following is a specification.

The object of the invention is to provide a railroad tie of a construction adapting it 10 for use as a substitute for the wooden or timber ties now commonly employed as a means of economizing in expense while conserving the supply of timber, and at the same time of securing an effect in the sup- 15 port of the rails which is similar in the matter of resiliency or the cushioning effect obtainable by the use of wooden ties, with increased durability and general weather resis- 20 ting qualities, and to this end the invention consists in a construction and combina- 25 tion of parts of which a preferred embodiment is shown in the accompanying drawings, wherein:

Figure 1 is a perspective view of the tie 25 showing a portion of a rail seated in opera- tive position thereon.

Fig. 2 is a transverse section on the plane indicated by the line 2—2 of Fig. 1.

Fig. 3 is a longitudinal section on the plane indicated by the line 3—3 of Fig. 1.

Fig. 4 is a detail view in perspective of one of the pockets or seat members for the 30 inserts or anchor blocks.

Fig. 5 is a similar view of one of the 35 inserts or anchor blocks.

Fig. 6 is a sectional view taken longitudinally through one of the anchor blocks to illustrate the engagement of the rail securing spike therewith.

Fig. 7 is a detail view of one of the 40 spikes.

In the construction illustrated the tie body 45 consists essentially of the top and bottom plates 10 and 11 preferably of metal spaced apart and connected by rivets 12, the interval between said plates being occupied by a yielding or cushioning filling 13 consisting of laminated paper or similar fibrous material preferably treated with creosote or other 50 preservative and in practice it is preferred to use tar paper in this connection arranged in layers co-extensive with the plates and held in a more or less compressed condition by means of the rivets which extend there- 55 through.

Supported by the upper or top plate, as

by being riveted as at 14 to the under surface thereof are the pocket or seat members 15 flanged as at 16 for contact with the under surface of the top plate and each embodying a plurality of looped or saddle-like seats 17 adapted for the reception of movable preferably metallic inserts or anchor blocks 18. At the upper inner sides of the pockets or seats are formed shoulders 19 defining the lower sides of recesses 20 which when the railroad or track rail 21 is in place are bounded by the under surface of said rail, and the inserts or anchor blocks are provided with extensions 22 which fit in 60 said recesses and thus lie between the under surface of the track rail and the shoulders 19 to the end that the bearing of the rail upon said blocks serves to retain the latter at their inner ends in proper seated relation 65 to the pockets. At their outer ends the inserts or anchor blocks are provided with offsets 23 which are overlapped and engaged by the edges of the top plate which project 70 inwardly over the seats or pockets to form 75 lips 24. In positioning the inserts or anchor blocks therefor they may be inserted into the seats or pockets in an inclined position so as to dispose the offsets 23 beneath the lips 24, after which the inner ends of 80 said inserts or blocks may be depressed to 85 position their upper surfaces in the plane of the upper surface of the top plate whereupon the arrangement of the foot of the rail in bearing relation with the inserts or blocks 90 and the fastening of the same to the blocks 95 will serve to lock the latter firmly in place in the body of the tie.

The means which are preferred to lock the rails in place to the inserts or blocks consist of pliable spikes 25 headed in the usual way as at 26 to engage the edges of the rail base and driven into curved or return sockets 27 in the inserts or blocks to the end that as each spike progresses it is bent or turned 100 upon itself to assume a hook-like form indicated in detail in Figs. 3 and 6. The entrance end 28 of the socket is preferably rectangular to correspond with the angular portion 29 of the spike while the outlet terminal 105 of the socket as shown at 30 is preferably round and is accessible from the surface of the insert or block to permit when desired, of the introduction into the socket of oil or grease to minimize the tendency of the 110 spikes to corrode, a plug or stopper 31 being then applied to close said outlet end of the

socket. It is also preferable in practice that the spikes be tinned or galvanized or similarly treated to add to their durability by minimizing the tendency to rust.

5 It is obvious that the body portions of the ties constructed as indicated may be laid in the roadbed in the ordinary way and with a facility equal to that of the wooden or timber ties now in common use, and that the 10 subsequent positioning of the inserts or anchor blocks and the locking of the latter in place by the spiking of the rail bases thereto may be accomplished with the minimum expenditure of time and effort and with a certainty 15 and accuracy which insures the proper gage of the rails after the tie bodies have been properly positioned.

It should be noted moreover that aside from the marginal plates and the means attached to the upper plate for seating and fastening the rail bases the tie is composed entirely of a relatively inexpensive and ordinarily waste material and that even under heavy compression necessary to give the required 20 solidity to the tie the filler will possess a resilient or cushioning property which compares favorably with that of a wooden tie and in some particulars has advantages over the material ordinarily used in that it is less subject to permanent distortion or uneven 25 compression due to the heavy weight imposed thereon by the passing trains, particularly as the means interposed between the track rails and the filler serve to distribute the weight so that the entire volume 30 of the tie is subjected to pressure rather than only those portions which are immediately adjacent to the rail bases.

What is claimed is:

40 1. A railroad tie having a marginal top plate, and inserts or anchor blocks fitted in openings in the top plate and provided with curved spike receiving sockets.

45 2. A railroad tie provided with a top plate having depending seats or pockets, metallic

inserts or anchor blocks removably fitted in said seats or pockets and having their inner ends disposed within the area occupied by a rail seated upon the tie, the outer ends of said inserts or anchor blocks having an interlocking engagement with the seats or pockets.

50 3. A railroad tie provided with a top plate, seats or pockets depending from the top plate in communication with openings in the latter, removable inserts or anchor blocks fitted in said seats or pockets and having interlocking engagement at their remote ends with the adjacent edges of the top plate, the inner ends of said inserts or blocks being disposed within the area occupied by the base of a rail seated upon the tie for receiving the pressure of said rail, and rail fastening means having an interlocking engagement with said inserts or anchor blocks.

55 4. A railroad tie provided with a top plate, seats or pockets depending from the top plate in communication with openings in the latter, the adjacent edges of the top plate overhanging the outer ends of said seats or pockets and the inner ends of said seats or pockets having shoulders defining the lower sides of recesses disposed within the area of a rail base seated upon the tie, inserts or anchor blocks fitted in said seats or pockets 70 and provided with offsets for engagement with the overhanging edges of the top plate and with extensions occupying said recesses for receiving the pressure of a superposed rail base, said inserts or blocks being provided with curved spike sockets provided with exposed entrance and exit terminals of which the latter are fitted with removable blocks, and pliable spikes engaging said sockets and bendable thereby to cause an 75 interlocking engagement between the spikes and the blocks.

80 In testimony whereof I affix my signature.

GEORGE F. A. OCHS.
